United States Patent Office

Des. 225,710
Patented Jan. 2, 1973

225,710

TABLE

Lawrie G. McIntosh, Islington, Ontario, Canada, assignor to Carolina Enterprises, Inc., Tarboro, N.C.

Filed Aug. 3, 1970, Ser. No. 24,262

Term of patent 7 years

Int. Cl. D6—03

U.S. Cl. D6—146

FIG. 1

FIG. 2

FIG. 3

FIG. 4

FIG. 5

FIG. 1 is a perspective view of a table showing my design;

FIG. 2 is a top view of the table;

FIG. 3 is a view of the table in side elevation;

FIG. 4 is another view in side elevation showing one of the four identical quadrants; and

FIG. 5 is a bottom view of the table.

I claim:

The ornamental design for a table, as shown and described.
